(57) **CLAIM**

The ornamental design for a coffee maker, as shown and described.

DESCRIPTION

FIG. 1 is a front perspective view of a first embodiment of a coffee maker showing our new design; FIG. 2 is a front elevation view thereof; FIG. 3 is a top plan view thereof; FIG. 4 is a rear elevation view thereof; FIG. 5 is a bottom plan view thereof; FIG. 6 is a left side elevation view thereof; FIG. 7 is a right side elevation view thereof; FIG. 8 is a front perspective view of the coffee maker of FIG. 1 in use, with contextual objects and features shown in broken lines; FIG. 9 is a front perspective view of an alternate embodiment of a coffee maker showing our new design; FIG. 10 is a front elevation view thereof; FIG. 11 is a top plan view thereof; FIG. 12 is a rear elevation view thereof; FIG. 13 is a bottom plan view thereof; FIG. 14 is a left side elevation view thereof; FIG. 15 is a right side elevation view thereof; and, FIG. 16 is a front perspective view of the COFFEE MAKER of FIG. 9 in use, with contextual objects and features shown in broken lines.

The broken lines illustrate portions of the coffee maker that form no part of the claimed design.

1 Claim, 10 Drawing Sheets
